UNITED STATES PATENT OFFICE.

MATTHEW H. LOUGHBRIDGE, OF BOGOTA, NEW JERSEY.

RAILWAY-TRAFFIC-CONTROLLING SYSTEM AND APPARATUS.

Application filed March 23, 1923. Serial No. 627,214.

This invention relates to railway traffic controlling systems and the apparatus used therewith and more particularly to a system for automatically controlling trains in which signals are conveyed between locomotive devices and devices on the track which are applied through translating means to give indications of the condition of the track and to automatically control the train brakes with relation to speed and track conditions. The invention as herein described includes a complete system for application on single and double track railroads and which permits the operation of trains on track where the system is not operative. The objects of the invention are: to provide a novel type of magnet on the track, to provide an amplifier responsive to the track magnet, to provide a stop transformer responsive to a laminated bar on the track, to provide a translating device for the circuits, to provide a speed control mechanism, to provide a manual release for the speed control, to provide a centrifuge for determining speed, to provide a magnetic contacting shoe, to provide operating circuits on the locomotive with a cut-out arrangement and to provide operating circuits for single and double track operation. These and other objects of the invention are described in greater detail in the following specification and the accompanying drawings, in which:

Figs. 1, 2, 3 and 3^a show sectional elevations of the track magnet;

Fig. 4 shows a side elevation of the track magnet;

Fig. 5 is an end elevation of the amplifier or translating inductor responsive to the track magnet and Fig. 6 is a sectional elevation of this device.

Figs. 7 and 8 show the magnetic frame of the stop transformer;

Figs. 9, 10 and 11 show the translating device operating a semaphore indicator and a three position valve;

Figs. 12 and 13 show partly in section the speed control mechanism;

Fig. 14 shows in section the speed control valve and manual release valve;

Fig. 15 is a top view of the manual release;

Fig. 16 shows in section, the cut-out valve;

Fig. 17 shows the engineer's brake valve and reducing valve;

Fig. 18 is an outline of the centrifuge;

Fig. 19 is a sectional view of the centrifuge showing the details of construction;

Fig. 20 is a view of the centrifuge, partly in section, with the mechanism cover removed showing its application;

Fig. 21 shows details of the construction of the centrifuge;

Fig. 22 is a side elevation of the magnetic contact shoe showing its relation to the track;

Fig. 23 is a front elevation corresponding to Fig. 22;

Fig. 24 is a detail of the shoe head.

Fig. 25 shows the locomotive wiring including the wiring of the cut-out system;

Fig. 26 shows the wiring of the track apparatus for single track operation;

Fig. 27 shows the wiring of the track apparatus for double track operation and Fig. 28 is a complete diagram of one unit of the braking system.

The track magnet.

The track magnet is used to transmit the impulse from the track to the inductor on the locomotive and also to deflect the field of the stop transformer. This magnet is clamped against the outside of the running rail with no part projecting above the top of the rail so that it does not interfere with established clearances. The magnet consists of a pair of elongated poles with a plurality of energizing coils between these poles so that the length of the magnet may be varied to suit conditions and to prolong the impulse as desired. These coils, when energized, set up a magnetic field adjacent to the rail head which magnetizes the inductor on the locomotive. The entire magnet is clamped to the rail without previous preparation.

In Fig. 1, showing a cross-section at the bracket, 11 represents the rail of the track, 12 is the bracket secured to the rail by the hook bolt 13. The inner pole of the magnet is represented by the plate 14 which is placed in contact with the rail head as shown. The outer pole is represented by the laminated bar 16, reinforced with the angle pieces 17 and supported by the non-magnetic bracket 15 which seats on bracket 12 and is secured by the hook bolts 13. The end of the outer pole is preferably inclined in ramp form as indicated in Fig. 4. Fig. 2 shows a cross-section of the magnet at the energizing coil 18. The laminations

of the bar 16 are extended to engage the core of the coil as shown. In certain applications it may be desirable to detect any misalignment or displacement of the outer pole 16 and for this purpose the arrangement shown in Fig. 3 may be used. The bracket 19 is rigidly secured to the outer pole 16 and carries the insulated contact 20 which establishes a circuit between the contacts 21, 10 which are rigidly secured to the bracket 12. The mis-alignment of the outer pole with the rail will be detected by interrupting the circuit connected to wires 21^a controlled by contacts 21. This circuit may be arranged 15 to control one of the track magnets such as 312 in Fig. 27 or it may control a special device for detecting purposes, this application, however, not being shown in the drawings. The laminated pole may be placed 20 adjacent to the rail head as shown in Fig. 3^a in which the pole is indicated by 16^a supported by the continuous bracket 12^a and the outer pole is indicated by the angle 14^a.

25 *The mechanical amplifier.*

The locomotive inductor that responds to the magnetism of the track magnet consists of an electric generator having a rotating armature and poles but no field for these 30 poles. The magnetic field of these poles is supplied by the track magnet when energized. This inductor is indicated by 23, Fig. 5 having pole 24 arranged to align with one pole of the track magnet and pole 25 arranged to align with the other pole of the 35 track magnet. The poles 24 and 25 are extended and it will be noted that pole 24 extends above the rail head as the flux from pole 14 is distributed through the rail head. 40 As the track magnet is entirely supported by the running rail it is apparent that it will be maintained in alignment therewith and as the locomotive inductor is also maintained in alignment with the running rail 45 it is apparent that a comparatively small air gap can be maintained between pole 24 and the rail head; this enables the air gap between the outer poles to be increased and enables the locomotive clearance line to slope 50 off as indicated by the line *c*.

The sectional view in Fig. 6 shows the construction of this inductor or amplifier in which the armature 27 rotates at high speed between poles 26, which are extensions 55 of the poles 24 and 25. A circuit is connected with this armature which operates the circuits hereinafter to be described. The armature 27 is driven by the motor 28 having the field 29 which is energized by a 60 source of current on the locomotive. The armature 28 may also be arranged to generate a high frequency alternating current for purposes hereafter to be described.

65 With this arrangement it will be noted that armature 27 runs idle and no current

is generated thereby until a magnetic flux is transmitted from the track magnet through the poles 24 and 25, the field 26 and the armature 27 when a current is generated caused by the flux of the track magnet amplified by the mechanical power supplied to the armature 27. If the armature is wound for, say 500 volts and rotating at high speed a considerable E. M. F. will be generated notwithstanding the air gap in the magnetic 75 circuit. The track magnet may be energized by direct or alternating current. When energized by direct current it is apparent that the direction of the current generated by the armature depends upon the polarity 80 of the field which is controlled by the polarity of the track magnet. This makes possible the use of a polarized system on the locomotive controlled by the polarity of the track magnet or the circuits associated therewith.

7 The stop transformer.

The stop transformer is used to change the conditions of proceed to stop when under 90 the influence of a track magnet by deenergizing a circuit. This consists of an inductor carried by the locomotive and having a pair of poles aligning with the laminated pole of the track magnet. This inductor 95 has a primary core energized by the high frequency current generated by the motor 28, or obtained from any other source, and has a secondary core with an air gap and a secondary winding. The secondary winding 100 is connected with the operating circuits and when deenergized causes a stop or retarding condition.

The stop transformer, 31, Fig. 7 has a primary core 32 with a suitable winding and 105 a secondary core 33 with a suitable winding. Below the primary core the poles 34 and 35 extend and are arranged to align with the laminated pole 16 of the track magnet. The alternative path for the flux from the primary 32 through the enlarged poles 34 and 35 and the laminated pole of the track magnet offers less reluctance than the path through the secondary core 33 with the air gap so that the flux is deflected from the 110 secondary and the circuit connected therewith is substantially deenergized.

115 It will be noted that the poles of the stop transformer will align with crossing frogs and the rails of turn-out switches as the train 120 proceeds along the track. The reactance however, of the solid iron of the track structure to the alternating flux of the transformer is such as to cause no material deflection of the flux, while the laminations of the 125 magnet pole forms a ready conductor for this flux. By increasing the frequency of the current energizing the transformer, this condition can be secured with a wide operating margin although it is believed 120 cycles 130

per second will be sufficient for most purposes.

Electric translating device.

5 In systems of this kind it is customary to use relays having armatures operating electric contacts for controlling the circuits. This invention is designed to avoid the use of relays and as far as possible to avoid the 10 use of electrical contacts of any kind as these are unreliable and difficult to maintain when installed on a locomotive. For this purpose a transmitting device is used having a rotating armature with a shaft connected to the 15 operating mechanism. This armature has a bias to a position corresponding to stop and is moved to the proceed position by the proceed circuit and maintained there by the secondary of the stop transformer. Most of the 20 operations of a plain relay, a stick relay or a polarized relay can be obtained by the use of this device. As shown in Fig. 9, this device consists of a magnetic yoke 41 having a field coil 43 and poles between which the armature 42 is pivoted for limited rotation as 25 defined by the stop 46 on shaft 44. A weight 45 secured to this shaft imparts a bias to the armature to take up the position shown as indicated by *b*. If the armature is moved 30 to the position indicated by *a* and the field coil energized it will remain in this position until the field is deenergized when the weight 45 will move it into the position *b*; in this position it will remain after the field is again 35 energized; thus energizing the field will hold the armature in the position to which it has been moved but will not, of itself, move the armature. The armature may be positioned mechanically, but for most purposes it is positioned electrically by having a winding 40 thereon energized by the same circuit as energizes a field coil so that the combined magnetic action of the field and armature will move the latter to the position desired when 45 the circuit is energized either by alternating or direct current. In application, the proceed circuit moves the armature to position *a*.

Fig. 10 shows two, two position translating devices coupled together to obtain a 50 three position effect. These devices are held together with the shafts 44 in alignment by the bolts 47 and 48 provided with suitable spacers. These bolts also support the motion plates 49 and 50 as shown. The operating mechanism associated with these plates is 55 shown in Fig. 11. The motion plates are provided with a slot 51 at one side in which the pin 52 slides and slot 53 on the opposite side in which the pin 54 slides. Attached to 60 the pin 52 is the vertical rod 55 and attached to pin 54 is the vertical rod 56, these rods being connected by the walking beam 57 to the centre of which the up and down rod 60 connects. This rod is weighted at 61 and 65 connects to the link 62 which operates the

three position valve of the train control mechanism; also by the connection 63, Fig. 10, it moves the semaphore indicator 65 pivoted on shaft 64.

Connected to the shaft of one of the translating devices is the arm 58, Fig. 11 and to the shaft of the opposite device the arm 59 connected; these arms therefore move with the armatures of these devices. When 58 is moved or rotated it raises pin 52 in the slot 70 which raises one end of the walking beam and gives a caution indication of the semaphore. When arm 59 is also rotated it raises pin 54 which raises the other end of the walking beam changing the caution indication to a clear indication. The order of this operation may be reversed as it will be noted that raising either end of the walking beam will give a caution indication and raising both ends will give a clear indication, while 75 lowering both ends gives a stop indication.

Train control mechanism.

The train control mechanism comprises a stepping valve which is under the joint control of the signal and the speed of the vehicle. Each step of this valve leads to a control or brake application unless and until a manual release is operated. In Figs. 12, 13 and 14, 100 indicates the stepping valve 90 which is operated by the ratchet wheel 94. This wheel is stepped around by the arm 92 counterweighted at 93 and having the detents 95 and 96 engaging wheel 94. When the support is withdrawn from this arm the 100 counterweight moves it down to the limits defined by the end 97 engaging stops on quadrant 98 as shown in Fig. 13; this moves the wheel 94 one step and the operation may be repeated each time the arm is raised. 105 This arm is provided with a cross-bracket 91 engaged by the ends of piston rods 87 and 89. When both of these piston rods are lowered the arm is without support but if either piston rod is raised, the arm is raised and supported with it and will be raised and lowered in response to the movements of a single piston rod.

The three position valve 67 operated by the signal device has a stop position indicated by *s*; a caution position indicated by *c* and a proceed position indicated by *p* corresponding with the indications of the signal as shown in Fig. 10. An air supply is connected to pipe 69 and the caution control 115 mechanism is connected to pipe 70. This pipe passes through a cut-out valve 75, Fig. 16 and by extension 77 connects with the signal cylinder 78, raising the piston rod 87 against the weight 88 and raising arm 92 120 at the same time. To delay the return of piston rod 87, the reservoir 80 may be connected with cylinder 78 by pipe 79 through a regulating valve 81. Thus the pressure in reservoir 80 must be reduced as well as the 125 130

pressure in cylinder 78 before piston rod 87 will return to the lowered position.

The centrifuge 83, Fig. 18 operates a valve 82 in response to speed which permits the 5 passage of air from pipe 69^a to pipe 84 connected with the centrifuge cylinder 85 and is so arranged that below a predetermined speed this cylinder is supplied with air, but above this speed the air in this cylinder is 10 exhausted through the right hand end of the bore where the plunger operates. When the air is exhausted from 85 the weight 90 restores piston rod 89 to the lowered position.

The illustration in Fig. 18 is merely a diagram of a centrifuge which may be constructed as shown in Figs. 19 and 20 hereafter described.

An independent mechanism may be provided to operate under a stop signal as 20 shown in Fig. 28 in which pipe 71 corresponds to pipe 70 and pipe 85' corresponds to pipe 84 pipe 85' being controlled by valve 86 which is set for a lower predetermined speed. It will be noted that with the valve 25 stem 66 in the position shown in s pipe 71 connects to exhaust which leads to a brake application in the manner explained in connection with the caution control. In Fig. 28, the corresponding parts are given the 30 same reference characters as in Figs. 10, 12 and 18 with an exponent "e." The valve of the centrifuge shown in Fig. 19 is used in this application.

The caution position of the valve stem is 35 shown at *c* in which pipe 70 connects with pipe 72 connecting with the audible signal 73. In this position the air from signal cylinder 78 and reservoir 80 exhausts through the whistle giving a preliminary warning for 40 reducing speed, and if the speed is reduced below the predetermined value before cylinder 78 is exhausted there will be no brake operation unless the speed should at any time while the caution conditions are established 45 exceed this predetermined value.

When a clear signal is established as indicated by the position of the valve stem at *p* both the pipes 70 and 71 are connected with the air supply 69, consequently the 50 signal cylinder of each control mechanism is under pressure and the speed of the train is not restricted in any way. With this arrangement it will be noted that arm 92 under a clear signal is maintained in the raised 55 position by the signal cylinder and speed may be varied to any extent, but under a caution or stop signal this arm is maintained in the raised position by the centrifuge cylinder operating under speed limitations. It will be observed that the valve stem 60 in the position *s*, Fig. 10, exhausts pipe 70 thereby exhausting cylinder 78 for a stop effect. This result may be obtained with the valve stem in the *c* position, that is, under a 65 caution signal, by suitably arranging the

ports in the valve stem but which has not been detailed on the drawing.

The cut-out valve in Fig. 16 is used where the operation of the system is to be suspended. As shown the valve stem 74 connects the 70 pipes 70 and 77; when this stem is raised, however, the pipe 77 is connected with the air supply pipe 69^a and pipe 70 is shut off. Pipe 77 under pressure, raises piston rod 77 and prevents the operation of the braking 75 mechanism. The operation of this valve will be described in connection with the operating circuits.

In order to avoid the use of springs, counterweights have been substituted as for 80 instance the weights 68 and 76 on the valve stems. If the operating connections of these valves should break the weights will bring them into position to operate the mechanism. The stepping valve is operated by releasing 85 air pressure and the cylinders 78 and 85 are provided with openings 101 above the normal position of the pistons so that if the cross bracket 91 or the arm 92 should break, these pistons would be raised to the top of 90 the cylinder and air would exhaust through 101 thereby detecting the failure. The stepping valve and the cylinders are held together by the supporting frame 99.

The manual release.

When the train control mechanism has operated to apply the brakes it is necessary that the brakes be released to enable the train to proceed under control and for this purpose 100 the manual release is provided. This device is arranged to operate in synchronism with the stepping valve so that for each step it must change its position in order to accomplish its purpose; it is also arranged so that any attempt to prematurely position the manual release will lead to an application of 105 the brakes.

The brake valve and manual release are shown in section in Fig. 14. The stepping 110 wheel 94 rotates the inner valve 106 having a row of ports 109 aligning with pipe 112 and another row of ports 108 aligning with pipe 111, the ports 108 and 109 being placed in staggered relation to each other. These 115 ports are spaced so that for each step of wheel 94 one port is brought into registry with one of the pipes 111 or 112. As shown in the drawing, port 108 is in registry with pipe 111 and therefore this pipe is in connection with the interior of the valve. When wheel 94 makes the next step pipe 111 will be closed and pipe 112 will be connected through port 109 with the interior of the valve, and so on, alternately, one pipe is 120 closed and the other connected with the valve interior.

The manual release valve 113 has an interior member 114 with ports 115 and 116 in 125 staggered relation; pipe 112 is connected to 130

register with port 115 and pipe 111 is connected to register with port 116 and so arranged that when one of these pipes is open to the interior of the valve the other is closed. The inner valve is moved to open and close these pipes by the handle 119 operating a worm which engages the worm quadrant 118 as shown in Fig. 15; this insures a slow release giving the brakes time 10 to control the speed of the train.

The brakes are applied by exhausting air through the port 117 from the interior of the stepping valve. As shown, it will be noted that both pipes 111 and 112 are closed 15 and no air can escape. Now if wheel 94 moves one step, pipe 112 will connect the interior of 106 to the interior of 114 and exhaust through 117. To stop this exhaust the manual release is operated to close the port 20 115. This, however, opens the port 116 to pipe 111 and when wheel 94 makes the next step, this pipe will connect with the interior of 106 and lead to an exhaust again until the manual release is changed back to its 25 former position. Thus, each movement of the stepping wheel requires a movement of the manual release to synchronize therewith in order that normal conditions may be restored. If the manual release is prematurely 30 moved, as for instance in Fig. 14, then pipe 111 would be open at both ends and lead to an exhaust. The operation of this apparatus has been described in connection 35 with a pressure brake system but it can be adapted for operation by a vacuum brake system or by an electric system without departing from the principles herein disclosed.

The reducing valve.

40 The reducing valve is used to obtain a graduated effect in the application of the brakes usually measured by a certain number of lbs., pressure reduction in the brake pipe. The reducing valve 124 is shown in section in Fig. 17 and connects by pipe 110 to the interior of the stepping valve 100. The engineer's valve is indicated by 122 and connects by pipe 123 with chamber 125 where the pressure in said pipe acts on the piston 50 126 forcing it against spring 127 which abuts on 128. The hollow plunger as shown moves with piston 126 and when it projects beyond 128 until port 130 is uncovered, air escapes into chamber 131 connecting with pipe 110. 55 As the pressure in 131 builds up, the air through the opening 129 equalizes the pressure on piston 126 and the spring restores it to the position shown.

It is apparent that when the pressure in 60 chamber 131 is reduced the pressure in chamber 125 will move the piston forward and hold it there until the pressure in 131 is raised or until the pressure in chamber 125, which corresponds to the pressure in the 65 brake pipe is reduced so that spring 127 can

overcome it and move the piston back. Thus, after a certain train line reduction the escape is cut off.

Attention is called to the fact that the stem connecting stepping wheel 94 with 106 70 is hollow and a breakage will lead to the escape of air.

The centrifuge.

The centrifuge is used to operate a valve 75 at a predetermined speed and is operatively connected with the centrifuge cylinder of the train control mechanism. The centrifuge is driven by a bevel gear from the axle of one of the running wheels of the locomotive and is provided with certain safety features which operate to detect a failure of the moving parts. Referring to Fig. 19, the mechanism case is indicated by 141, the gear case by 142 and the supporting arm 80 by 143 which engages a shaft 144 bolted against the end of the axle of the running wheel through the plate 145 and the bevel gear 146, Fig. 20. This gear is protected by a cover 147 and meshes with the bevel gear 148 secured on the driving shaft of the centrifuge 149 as shown. This shaft is mounted on ball bearings as indicated in the sectional drawing and is provided with a head 150 which is fixed to the shaft and a 85 sliding head 151 which has a pin engaging the key-way 156. Pivoted to the fixed head 150 is the arm 152 and pivoted to the sliding head is the forked arm 153, these arms being pivotally connected through the disc weights 154 and as the shaft speeds up these weights move out from the centre compressing spring 155 according to the standard construction of a centrifuge.

The operating arm 157 is pivoted to the 105 mechanism at 158 and is engaged by the collar 159 of the sliding head 151 so that this arm moves with the sliding head and the outer end engages the valve stem 161. This arm is constructed in the form of a 110 lever with its outer end magnifying the movement of the sliding head. The valve stem 161 is provided with a recess 160 in which the end of arm 157 has a free movement. As this arm is moved to the left the 115 spring 162 withdraws the valve stem until it is stopped by the pin 162^a and further movement of arm 157 will not influence the valve stem; in the return of this arm it becomes effective to move the valve after 120 the lost motion in recess 160 is taken up.

The valve stem moves in a valve sleeve 163 which is adjustably positioned by the screw thimble 164 relative to the frame. The valve is provided with an annular 125 groove near the end 165 which, when aligning with the opening 170, makes a clear passage to pipe outlet 167 and exhausts this outlet through 170. The valve also has an opening through the centre indicated by 130

the dotted lines 166, which, when in the position shown connects the air chamber 168 with the pipe outlet 167 and charges this pipe outlet with air from the air pipe 169 until the valve moves to the right far enough to close the opening to pipe outlet 167. It will be noted that should arm 157 break spring 162 will move the valve into position to exhaust pipe outlet 167 which is the controlling position; this action is assisted by the air pressure in chamber 168 under the end of the valve.

A collar 170 is secured to the frame 141 and to the collar the legs 171 are riveted. 15 These legs form part of the supporting cage 172 and 173 which is pivotally connected to the supporting block 174 at 176 this block being pivotally suspended from a vertical rod 175 the other end of which is secured 20 to the frame of the locomotive. The pivot 176 permits the mechanism to adjust itself for the spring action of the wheel and pivot 175 permits side play for the swaying of the wheels relative to the frame. This attachment is equivalent to a universal joint. 25

An air supply is required for this centrifuge which is obtained from pipe 179 secured to the fixed disc 178 where it connects with the groove 180, Fig. 21. This disc is 30 placed against the disc 177 where the groove 181 normally registers with the groove 180 and the supply pipe 169 connects with the groove 181. This permits a free movement of the mechanism on pivot 176 without applying a strain on pipes 169 or 179. If the supporting rod 175 should break a strain would be thrown on pipe 179 causing a fracture and if the shaft 144 should break, the left end of the mechanism would fall down 35 causing rotation on pivot 176 through a considerable arc; this would align groove 180 with groove 182 and as the latter connects to exhaust, this would exhaust the air in pipe 179 which would lead to the detection 40 of the trouble owing to the leakage of air. This movement may also be arranged to exhaust pipe 169.

An air supply is connected to the moving parts of the centrifuge from pipe 169^a 45 through the casing 191 by passage 190 to the annular groove 189 in the member 189^a bolted to the end of the shaft. A passage from the annular groove connects to the opening 186 in the centre of the shaft which 50 is thereby maintained at air pressure. This passage terminates in chamber 185 in the bevel gear 148. A connection may also be made through 187 with the bearing of arm 152 which may be provided with a passage 55 188 terminating against the weights 154 as indicated by the dotted outline, Fig. 20. If the bevel gear 148 should break or become detached from the shaft it is apparent that 60 the air in chamber 185 would escape. If 65 shaft 149 should break, or if the supporting

head 150 or arms 152 or weights 154 become detached there will be an escape of air which will lead to a detection of the failure and this escape will continue until the failure is remedied. If connected with the air brake system, the escaping air will lead to an application of the brakes.

In order that the shaft may move freely and at the same time provide it with an air supply, an air lock is used where the air enters the shaft as shown in section in Fig. 19. This air lock consists of dovetailed sections indicated by 193, one section fitting on the shaft and the corresponding section fitting in the casing 191. When assembled, these sections provide annular grooves, partly in the stationary casing and partly in the shaft and in these grooves the washers 192 are loosely placed. An air tight cap is provided on the outer end of casing 191 and any escaping air between the rotating members on the shaft and the casing holds these washers against the face of the groove thereby forming a seal which prevents the air from escaping.

The magnetic shoe.

The magnetic shoe is arranged to make an electrical contact with a ramp on the track and in order to insure an intimate and reliable contact the shoe is magnetized and maintains a magnetic grip on the iron of the ramp as the shoe passes along the ramp. The shoe is constructed in the form of an L shaped lever, a pair of rollers are secured to the horizontal arm together with a magnet coil and the vertical arm, which is about three times the length of the horizontal arm terminates in a cam which operates a circuit controller.

Referring to Figs. 22 and 23, 201 is the track rail supporting the running wheel 202. A stringer 203 is secured to the end of the sleepers supporting the T iron 204 of the ramp and to which the contacting plates 205 are bolted. This construction makes these plates readily renewable when worn.

The locomotive bracket 206 is secured to the frame of the locomotive and supports the horizontal arm 207 by the pivot 208. The arm 207 is preferably made from non-magnetic material and supports the magnetic bar 209 of the shoe head. This bar is provided with bearing plates 210 at either end which form bearings for the rollers 212 on the pivots 211. Between the rollers the magnet coil 213 is placed as shown. The arm 207 is provided with a balance lever 215 upon which weight 214 is adjustably positioned. The force required to raise the shoe head can thus be adjusted by the counterweight 214.

The vertical arm 216 of the shoe is pivoted at 208 and has an extension 217 and

connection 218 by means of which it is adjustably secured to horizontal arm 207 and moves therewith. The arm 216 has an extension supporting weight 219 to the right of pivot 208 which applies a bias to this arm tending to move it to the right or controlling position in case the shoe head should become detached. Arm 216 is guided by bracket 220 and limited in its movement by screw 221.

The arm 216 terminates in a cam 222 which engages roller 223 of plunger 224 moving in the bracket 225. This plunger is forced downwards by the coil spring 226. The insulated contact member 227 is also carried by the plunger and makes contact with 229 in the lowered position as shown or with contact 228 in the raised position. More than one contact member may be used as required by the operating circuits.

In operation, the rollers of the shoe engage the contact plates of the ramp and the shoe head is raised or displaced thereby. Due to the lever action this displacement is magnified in the movement of cam 222 so that a slight displacement will move the roller over the rise of the cam and thereby produce a controlling effect. The movement of plunger 224 is steady although the shoe displacement may vary due to irregularities in the ramp. When the shoe runs off the ramp, the weight of the head moves the cam 222 to the left and raises plunger 224. When a train is running at high speed there is considerable impact between the shoe and the ramp which may be minimized by making the force to displace the shoe as small as possible and for this purpose the counterweight 214 is provided. It is, however, essential to obtain a reliable contact between the shoe and the ramp and for this purpose the shoe is magnetized after it has been displaced by a circuit controlled by contacts 227 and 229. This circuit energizes coil 213 which magnetizes bar 209, plates 210 and rollers 212, each roller forming the pole of a magnet the armature of which is composed of the ramp plates 205. The rollers are thus magnetically held in intimate contact with the ramp and, it will be noted that the rollers rotate in the plane of the lines of force from the coil 213 without cutting the lines of force or changing the magnetic circuit so that there is no resistance, magnetically, to the rotation of these rollers. With this construction an intimate and reliable contact is obtained between the ramp and the shoe while the wear and the impact is reduced to a minimum.

60 The locomotive wiring.

The locomotive wiring as shown in Fig. 25 has one side arranged for inductive operation and the opposite side arranged for mechanical operation, the effects—from

each of these operations are co-ordinated to control the train and give suitable indications.

Referring to the drawing, 251 is a source of current driving the motor 28 which in turn drives the A. C. generator 252 and the armature 27 of the amplifier 23. The A. C. generator 252 energizes the primary coil 255 of stop transformer 31 by wires 253 and 254 so that while motor 28 is running this coil is continuously energized. The secondary coil 256, by wires 257 and 258 energizes the field coil 43^a of the translating device 41 to the left; this will hold armature 42 in the position to which it has been moved. When the stop transformer 31 comes under the influence of a laminated track bar, the secondary coil is substantially deenergized and armature 42 assumes the stop position as shown. If the track magnet is energized armature 27 of the amplifier generates a current in wires 259 and 260 which energizes the field coil 43 and the armature 42, thereby causing this armature to assume the proceed position raising the arm 58. When moved to the proceed position the secondary current from the stop transformer maintains it in this position after this transformer is moved from the influence of the track magnet as explained in the description of the electric translating device.

When the shoe engages a ramp the circuit of field coil 43^a of the translating device to the right is interrupted at contact 227. This circuit may be traced from battery 261, contact 227, wire 262, coil 43^a and wire 263 to battery. This permits armature 42 to assume the stop position as described. If the ramp is energized, a current is picked up through the shoe head which is insulated from the locomotive and by wire 268 energizes coil 43 and armature 42 and returns to ground through wire 269. This moves armature 42 to the proceed position where it will remain when coil 43^a is again energized by the shoe running off the ramp.

When the shoe engages a ramp a circuit is established from battery 261 through contact 227, now closed to wire 264 to coil 213 magnetizing the shoe head and by wire 266 and rheostat 267 to battery 261. The rheostat enables the magnetism of the shoe to be adjusted to suit weather conditions.

For single track operation it is desirable to transmit a signal from the locomotive to the track. This signal is transmitted inductively by the magnets 275 and 276. These magnets are energized by the A. C. generator from wire 271, contact 231, wire 272, magnet 275, wire 273, magnet 276 and wire 274 and are controlled by the shoe.

7 The cut-out system.

The cut-out system is provided so that a train equipped with this system may run

on track which is not equipped and provided means for operating the cut-out valve to suspend the operation of the train control system and for obscuring the indication of the semaphore. This system is operated by the circuit shown in Fig. 25 in which the hand generator 286 drives the armature 287 and by wire 288 energizes the armature 282 and field coil 289 of the translating device 281; 5 this circuit returns by wire 290, switch 291 and wire 292 to the armature 287. While switch 291 is in the position shown and the hand generator is operated at speed the armature 282 is positioned to move the banner 283 over the semaphore 65 and the arm 284 raises the valve stem of the cut-out valve 75. The air connections for the cut-out valve are shown and described in connection with Fig. 16. This provides a temporary 10 means of suspending the operation of the system as long as hand generator 286 is operated. If, when armature 282 is in the released position the double pole switch 291-298 is changed to the right, then a circuit will be established from battery 293, wire 299, contact 298, wire 297, field coil 296, wire 295 and push button 294 to battery. This will energize the field of 281 and maintain the suspension of the system. Thus 15 20 25 30 35 40 45 50 55 60 65 70 75 80 85 90 95 100 105 110 115 120 125 130

After the system is suspended it may be permanently suspended by changing the position of switch 298 which is designed to make contact before 291 opens its circuit. The hand generator 286 and the switch 298 are, preferably so located that they cannot be operated by the same person at the same time, thus requiring the concurrent action of two people for permanently suspending the operation of the system.

After the system is suspended it may be brought into action by the push button which is located close to the hand generator. This push button opens the circuit of the holding coil 296 permitting the apparatus to assume its normal position as shown. The system may also be brought into action by moving switch 298 into the position shown which interrupts the circuit of the holding coil 296. The cut-out valve 75, Fig. 28 may be coupled to be operated by the arm 284 of the cut-out device 281, similarly to valve 75.

Double track wiring.

A plan of double track wiring suitable for operation with this system is shown in Fig. 27 in which train movements are in the direction indicated by the arrow. The track rails are indicated by 301 and 302 and the track is divided into blocks indicated by the letters *a*, *b*, and *c* by insulated joints 303. Each block is provided with a track battery 304 and with a track relay indicated by a letter corresponding with the letter of the

block. The track relay is connected by wires 305 to the track rails as shown.

On one side of the track the ramp 306 is located connected by wire 307 through a front point of the track relay and by wire 308 to battery 309, the other side of this battery being grounded on the track rail. This ramp will energize the circuit grounded on wire 269 on the locomotive through the shoe when the block immediately ahead of 75 the ramp is clear.

On the other side of the track the track magnet 311 is located having the energizing coil 312 connected by wire 313 to battery through the front point of relay 314 so that when this relay is energized the track magnet is energized. For simplicity in the wiring diagrams it should be noted that a wire starting with an arrow head is assumed to be the source of energy and a wire ending in an arrow point is assumed to be the common return; the first wire is sometimes marked B and the latter O. Relay 314 is controlled by wire 315 through the front contact of the track relay for the first block, wire 316 and the front contact of the relay for the next block. Thus the track magnet is energized when the first block and the succeeding block are clear. This is according to standard practice.

Single track wiring.

The wiring for single track operation is shown in Fig. 26, that is, where train movements are in both directions on the same track. This arrangement provides an absolute block protection against opposing movements between the sidings on a portion of single track and, at the same time provides for following movements with a train spacing according to the block arrangement. In this installation the track may be divided into sections or blocks as indicated by *a*, *b*, *c*, *d*, *e*, *f*, *g*, *h*, and *j*. The portions *b*, *d*, *f* and *h* are about equal in length to the standard length of block. The portions *a*, *c*, *e*, *g*, and *j*, opposite the rams or magnets are short track sections and are arranged to be included in the block system ahead of the train when the train runs in either direction. 110 Each section is provided with a track battery and a track relay similar to Fig. 27, the track relays being lettered *a*, *b*, *c*, *d*, *e*, *f*, *g*, *h*, and *j*, to correspond with the portions of track similarly lettered. For the sake of simplicity, connections to these track relays have not been shown.

Directional control relays 321 are provided at each track magnet location for traffic from left to right and directional control 125 relays 322 are provided for traffic from right to left. A relay 321, for instance, opposite section *a* is controlled by wire 323, track relay *b*, wire 324, track relay *c*, wire 325 and relay 321 at location *c* which is connected to 130

battery. Relay 321 at location *c* is controlled by a circuit similarly lettered through track relays *d* and *e*, and relay 321 at location *e*. Relay 321 at location *e* is, in turn, 5 similarly controlled by track relays *f* and *g*; and relay 321 at location *g* is similarly controlled by track relays *h* and *j*. It will be noted from this arrangement that if a train enters upon section *j* and deenergizes relay 10 321, at location *g*, this will, in turn, deenergize all of the directional relays 321. This will set the indicator 338' at the opposite end of the section controlled by wire 358 to the stop position and will also deenergize coil 312 of the track magnet for section *a*, so 15 that a train cannot enter from this direction without receiving a stop signal and it will be noted that this condition is maintained while the train proceeds through the entire single track section. This is an absolute 20 block for head-on protection.

For traffic in the opposite direction a similar operation is required relative to relay 322 at section *j*. This relay is controlled by 25 wire 327, relay *h*, wire 328, relay *g*, wire 329 and relay 322 at *g*, which connects to battery. Relay 322 at location *g* is, in turn, controlled by wire 327, track relay *f*, wire 328, track relay *e*, wire 329 and relay 322 at 30 location *e* to battery and so on throughout the remaining block sections. If a train therefore, enters upon section *a* relay 322 at section *c* is deenergized. This causes the other directional relays 322 to become de- 35 energized and to remain deenergized while the train is proceeding in this direction. This deenergizes wire 357 setting the indicator 339' in the stop position and deenergizes the track magnet opposite section *j*.

When a train, moving say from left to right, enters a portion of track, it is desirable that another train should be able to follow the preceding train as closely as the block system will permit. For instance, 45 when the rear of the first train has cleared section *c* it would be good practice to permit a following train to enter at section *a*; and when the first train had cleared section *e*, it would be satisfactory to permit a following 50 train to enter section *c*. This arrangement I secure by a signal transmitted from the train to the track apparatus in combination with the wiring arrangement shown. For this purpose stick relays 337 are provided for traffic from left to right and stick 55 relays 338 are provided for traffic from right to left. The stick relay 337 opposite section *d* is energized when the track relay *d* is deenergized and when an impulse is transmitted to wire 332 through the coil 333. When 60 therefore, the head of a train reaches section *e*, the rear end will have cleared section *c* as the block is usually of a length greater than the train, and the track relay *d* will be 65 deenergized.

The coil 333 is arranged to align with the magnets 275 and 276 on the locomotive. The magnets 275 and 276 are spaced with relation to the shoe rollers 212 and with relation to the location of coils 333 and 336 and the 70 ramp 306. The leading magnet passes over the first coil on the track before it is energized by the displacement of the shoe by the ramp; likewise, the rear magnet is deenergized when passing over the last coil as the 75 shoe is then off the ramp. Thus, when moving from left to right with magnet 275 in the leading position, this magnet will not be energized when passing over coil 333, but magnet 276 will be energized at this time and will 80 inductively transmit an impulse to coil 333 which will pick up the stick relay 337. Also, when passing off the ramp, magnet 275 will be energized but will not influence coil 336 as its circuit is open due to relay *f* being energized and stick relay 338 is not picked up. The rear magnet, it will be noted, passes over this coil deenergized as the shoe is disengaged from the ramp. When the locomotive backs up in the opposite direction these 85 conditions are reversed with respect to coils 333 and 336.

The stick relay at *d* is picked up from coil 333, wires 332 and 331. A holding circuit is provided for this relay through wire 339, 95 relay 321 at section *c* deenergized and wire 340 through a front contact on track relay for section *c* energized. When the stick relay 337 is energized, a circuit is established from battery to wire 326 and wire 325, energizing the directional relay 321 at location *a* and thereby energizing the track magnet for section *a* and permitting a following train to enter the block. When the first train reaches section *g*, an impulse is transmitted to coil 100 333 which, by wires 332 and 331, picks up relay 337 at this location and a holding circuit is established through wire 339, directional relay 321 deenergized, wire 340 and track relay *e* energized. When this relay is 105 energized a circuit is established from battery to wire 326, wire 325, picking up the directional relay 321 at location *c* and permitting a following train to enter the block at that point or at point *a*. This relation 110 is maintained between any number of following trains.

In the opposite direction, the arrangement is similar to that described except that the energizing coil 336 takes the place of coil 115 120 333. This coil by means of wires 335 and 334, picks up relay 338 through the back point of the adjoining track relay. Relay 338 has a holding circuit through wire 341, back contact of directional relay 322 and wire 342 to battery through the track relay for section *g*. A similar arrangement is provided for the operation of the stick relay 338 for the succeeding blocks.

It will be noted that the holding circuit 125 130

for the stick relay is controlled by the directional relays deenergized and by the track relay energized. The track relay control immediately deenergizes the stick relay as soon as the train has encountered this section, and the directional control relay immediately deenergizes the stick relay when the normal conditions of the block are restored. The system is, thus, self-restoring from any condition.

The track magnets 312 are controlled by wire 337' through the directional control relay 321 for traffic in one direction and through the directional control relay 322 for traffic in the other direction. The block control of the ramps 306, which in this case give the distant indication, may control through relays 321 for one direction or through relays 322 for the other direction at two succeeding locations but have for the sake of simplicity been omitted from the plan.

The operation of the system will be understood by considering the movement of a train over the track equipped as in Fig. 27, with the locomotive wired as shown in Fig. 25. If blocks *a* and *b* are clear, magnet 312 is energized and ramp 306 is energized. The pole 311 shunts the flux from the stop transformer 31 and deenergizes holding coil 43^a of the translating device to the left, at the same time however, poles 24 and 25 are magnetized and the amplifier delivers an amplified current to the positioning coil 43 and armature 42 which holds the armature in the proceed position until the stop transformer has passed over bar 311 and the holding coil 43^a is again energized.

When the shoe 212 is displaced by ramp 306, the circuit of holding coil 43^a of the translating device to the right is deenergized but as 306 is energized, a current is picked up which energizes positioning coil 43 and coil on armature 42 which holds this armature in the proceed position until the shoe runs off the ramp and the circuit of the holding coil 43^a is again energized.

When block *a* is clear and block *b* is occupied, magnet 312 is deenergized. In this case the stop transformer deenergizes holding coil 43^a as described but poles 24 and 25 are not magnetized so that arm 58 moves to the stop position and rod 55 is lowered and remains in the lowered position after coil 43^a is again energized as this coil cannot position the armature. This causes the indicator 65 to give a caution signal which remains until an energizing magnet is encountered.

When blocks *a* and *b* are both occupied, magnet 312 is deenergized, producing the results just described and ramp 306 is deenergized so that when the shoe is displaced and the holding coil controlled thereby is deenergized, the positioning circuit from the ramp is not established, the armature

moves to the stop position and rod 56 is lowered giving the stop indication. As this coil, of itself, cannot position the armature, the latter remains in this position after the shoe passes off the ramp and the holding coil is again energized.

When the stop conditions are established on the locomotive and a location is encountered where the ramp is energized and the magnet deenergized, then the positioning coil of the device operated by the shoe will be energized moving the armature to raise rod 56 and give a caution signal.

When stop conditions are established on the locomotive and a location is encountered where the ramp and magnet both are energized; the ramp will operate as described to raise one side of walking beam 57 and the amplifier will be energized, generating a current which will energize the positioning coils of the other translating device, raising rod 55 and giving a clear signal.

When a train is running under a clear signal the brake controlling valve 67 is in the raised position which admits air to pipes 70 and 71 and thereby holds the arm 92 raised without regard to speed. Under a caution signal this valve exhausts the air from pipe 70 through the whistle 73 and when cylinder 78 and reservoir 80 have been exhausted, the piston is lowered removing one of the supports from arm 92. If the speed is below a predetermined value or if it has been reduced to this value during the time the whistle is sounding, the cylinder 85 is placed under pressure controlled by the centrifuge thus providing an independent support for arm 92. However, if the predetermined speed is exceeded, cylinder 85 is exhausted, or is not placed under pressure and arm 92 drops when cylinder 78 is exhausted. Thus under a caution signal a predetermined speed cannot be exceeded as long as the caution conditions remain.

The braking mechanism connected with pipe 71 operates similar to that described except that the valve 67 must be in the position corresponding to stop to exhaust this pipe and the predetermined speed which admits pressure to cylinder 85^a is set for a lower value than the speed which admits pressure to cylinder 85.

The arm 92 operates the stepping valve to apply the brakes, these, however, may be released as soon as handle 119, with its slow acting mechanism has operated the manual release. It will thus be noted that, under a caution signal, an audible signal is given for a time interval followed by an application of the brakes unless the speed is below a predetermined value. When the brakes have once been applied they can be released only after a time interval. When the system is suspended the signal cylinder is under pressure without regard to the position

of valve 67 and arm 92 is held in the raised position so that the braking mechanism is not influenced by the centrifuge.

In applying this invention it is to be understood that the style and arrangement of the track apparatus together with the responsive apparatus on the locomotive may be varied to suit the conditions under which the system is applied.

10 Having thus described my invention, I claim:

1. In a railway traffic controlling system, the combination of a track with a vehicle thereon, a magnet on said track having a 15 pair of poles clamped to one rail of said track, a device on said vehicle responsive to said magnet, the terminals of a circuit supported by said rail and a member supported by a pole of said magnet for controlling said 20 circuit.

2. In a railway traffic controlling system, the combination of a track with a vehicle thereon, a magnet on said track having a pair of poles, a device on said vehicle responsive to said track magnet, the terminals of a circuit supported by one pole of said magnet and a contact member supported by the other pole contacting with said terminals.

3. In a train control system, the combination of a track with a vehicle thereon, a laminated iron bar secured against and flush with the head of the rail of said track and a transformer on said vehicle having poles 35 aligning with said bar.

4. In a train control system, the combination of a track with a vehicle thereon, a laminated iron bar supported throughout its 40 length by a bracket clamped against the rail of the track and a device on said vehicle having poles aligning with said bar.

5. In a train control system, the combination of a track with a vehicle thereon, a laminated iron bar reinforced with angular 45 braces clamped against the rail of said track and a device on said vehicle having poles aligning with said bar.

6. In a train control system, the combination of a track with a vehicle thereon, a laminated member on said track and a transformer on said vehicle having a primary and a secondary winding, said transformer responding to said track member to deenergize said secondary winding, said transformer energized by a high frequency current whereby the track rails do not materially affect said secondary winding owing to their reactance to the frequency of the current.

7. In a train control system, the combination of a track with a vehicle thereon, a laminated member on said track below the level of the rails, a transformer on said vehicle having a primary and a secondary core, said secondary core having an air gap

and poles extending from said primary core 65 and aligning with said track member.

8. In a train control system, the combination of a track with a vehicle thereon, a magnet on said track having a laminated pole within the horizontal plane of the rail head, and a transformer on said vehicle having 70 a pair of poles aligning with said laminated pole whereby the flux of said transformer is deflected by said pole.

9. In a train control system, the combination of a track with a vehicle thereon, a transformer on said vehicle having a primary core with an energizing coil and a secondary core with an air gap and a secondary coil, and a laminated bar on said track 80 within the horizontal plane of the rail head and poles from said primary core aligning with said laminated bar whereby the secondary coil is deenergized.

10. In a train control system, the combination of a track with a vehicle thereon, a magnet on said track having a laminated pole, a motor driven amplifier on said vehicle responding to said track magnet, an alternating current generated by said motor 90 and a transformer energized by said alternating current and responding to said laminated pole.

11. In a train control system, the combination of a track with a vehicle thereon, a control mechanism on said vehicle, a magnet on said track and a motor driven amplifier on said vehicle responding to said track magnet, said motor also generating an alternating current for operating said mechanism. 100

12. In a train control system, a track with a vehicle thereon, a centrifuge mechanism having a rotating shaft driven by the movement of said vehicle, an air supply connected with said shaft and an air lock between said 105 shaft and said mechanism.

13. In a train control system, the combination of a track with a vehicle thereon, a centrifuge mechanism having a rotating shaft driven by the movement of said vehicle, an air supply connected with said shaft, and an air lock between said shaft and said mechanism comprising an annular groove and a ring in said groove.

14. In a train control system, the combination of a track with a vehicle thereon, a centrifuge mechanism having a rotating shaft driven by the movement of said vehicle, an air supply connected with said shaft, an air lock between said shaft and said mechanism comprising dove-tailed rings forming annular grooves and a ring in each of said grooves.

15. In a train control system, a track with a vehicle thereon, a centrifuge mechanism driven by the movement of said vehicle, a valve having a plunger operated by said mechanism, an air supply and a spring tend-

- ing to force said plunger into a predetermined position.
16. In a train control system, a track with a vehicle thereon, and a centrifuge having a rotating shaft driven from the running wheels of said vehicle, said centrifuge supported at one end by a shaft secured to the end of a wheel axle and at the opposite end by a suspended pivot.
- 10 17. In a train control system, a track with a vehicle thereon and a centrifuge having a rotating shaft driven from the running wheels of said vehicle, said centrifuge placed horizontally and supported at one end 15 through a universal joint by said vehicle.
18. In a train control system, the combination of a track with a vehicle thereon, a centrifuge mechanism having a rotating shaft driven from the running wheels of said vehicle, a shaft secured to the axle of said wheels, a bearing in said mechanism for said shaft and the opposite end of said mechanism supported through a universal joint by said vehicle.
- 20 19. In a train control system, the combination of a track with a vehicle thereon, a centrifuge mechanism having a rotating shaft driven by the movement of said vehicle, means for supporting said mechanism horizontally, an air supply connected with said mechanism and means for interrupting said air supply when said supports are broken.
- 25 20. In a train control system, the combination of a track with a vehicle thereon, a centrifuge mechanism having a rotating shaft driven from the movement of said vehicle, said mechanism placed horizontally, a universal joint for supporting said mechanism, an air supply for said mechanism and a yielding connection for said air supply at said universal joint.
- 30 21. In a train controlling system, the combination of a track with a vehicle thereon, of a controlling mechanism on said vehicle, said mechanism comprising a stepping valve with a weighted arm and means for operating said valve by gravity.
- 35 22. In a train controlling system, the combination of a track with a vehicle thereon, a controlling mechanism on said vehicle, said mechanism operated by a weighted arm, means controlled from the track for raising said arm and independent means controlled by the speed of the vehicle for raising said arm.
- 40 23. In a train control system, the combination of a track with a vehicle thereon, a controlling mechanism on said vehicle, said mechanism operated by a weighted arm, an air cylinder having a piston controlled by track conditions for raising said arm and another air cylinder having a piston controlled by the speed of the vehicle for raising said arm.
- 45 24. In a train control system, the combination of a track with a vehicle thereon, a controlling mechanism on said vehicle, a weighted arm for operating said mechanism, a plunger controlled by track conditions engaging said arm and another plunger controlled by the speed of the vehicle independently engaging said arm.
- 50 25. In a train control system, the combination of a track with a vehicle thereon, a controlling mechanism on said vehicle, an arm for operating said mechanism moving between fixed limits, a plunger for operating said arm and means for detecting when said plunger exceeds its normal movement.
- 55 26. In a train control system, the combination of a track with a vehicle thereon, a plurality of devices on the track located at different distances from the centre line of said track and controlled by traffic conditions, a controlling mechanism on said vehicle, a plurality of devices responsive to said track devices, translating devices operated by said responsive devices, said translating devices having rotating armatures placed with their axes in the same plane and means for operating said controlling mechanism by said devices.
- 60 27. In a train control system, the combination of a track with a vehicle thereon, devices on the track controlled by traffic conditions, a plurality of translating devices on said vehicle responsive to said track devices, said translating devices having rotating armatures with their axes in the same plane and means for operating a three position device by said translating devices.
- 65 28. In a train control system, the combination of a track with a vehicle thereon, a ramp on said track, a shoe on said vehicle engaging said ramp and displaced thereby, and means electrically controlled effective upon the initial displacement of said shoe for obtaining an intimate contact between said ramp and said shoe.
- 70 29. In a train control system, the combination of a track with a vehicle thereon, a ramp on said track, a shoe on said vehicle engaging said ramp and displaced thereby, an adjustable counterbalance for the weight of said shoe and means for obtaining an intimate contact between said ramp and said shoe.
- 75 30. In a train control system, the combination of a track with a vehicle thereon, a ramp on said track, a shoe on said vehicle engaging said ramp and displaced thereby and means for magnetizing said shoe by its initial displacement by said ramp.
- 80 31. In a train control system, the combination of a track with a vehicle thereon, a ramp on said track, a shoe on said vehicle engaging said ramp and displaced thereby, means for magnetizing said shoe and means for varying the extent of said magnetism.

32. In a train control system, the combination of a track with a vehicle thereon, a ramp on said track, a shoe on said vehicle engaging said ramp and displaced thereby, a magnetizing coil on said shoe and a rheostat in the circuit of said coil.
33. In a train control system, the combination of a track with a vehicle thereon, a ramp on said track, a shoe on said vehicle engaging said ramp and displaced thereby, said shoe having a pair of rollers contacting with said ramp and a magnetizing coil placed between said rollers.
34. In a train control system, the combination of a track with a vehicle thereon, a ramp on said track, a shoe on said vehicle comprising a magnetizing coil and a pair of rollers, said rollers forming the poles of a magnet and engaging said ramp.
35. In a train control system, the combination of a track with a vehicle thereon, a ramp on said track, and a shoe on said vehicle comprising a magnetizing coil and a pair of rollers, said rollers engaging said ramp and moving in the plane of the magnetic field created by said magnetizing coil.
36. In a train control system, the combination of a track with a vehicle thereon, a ramp on said track, a shoe on said vehicle engaging said ramp, a magnet on said track and an inductive device on said vehicle responsive to said magnet, means for communicating an independent effect to said vehicle by said ramp and by said magnet and means for co-operatively applying said effects accumulatively or deductively to control said vehicle.
37. In a railway traffic controlling system, the combination of a track with a vehicle thereon, a magnetic member on said track comprising a laminated iron pole extending parallel with the track, angle bars for reinforcing the corners of said laminated pole and brackets supporting said angle bars and a device on said vehicle responsive to said magnetic member.
38. In a railway traffic controlling system, the combination of a track with a vehicle thereon, a magnetic member on said track having a laminated iron pole, a device on said vehicle responding to said magnetic member and a plurality of bars for reinforcing said laminated iron pole, said bars arranged with an air gap between adjacent bars.
39. In a railway traffic controlling system, the combination of a track with a vehicle thereon, a magnetic member on said track having a laminated pole and an energizing coil, said laminations being increased in section to engage the core of said coil and a device on said vehicle responsive to said track magnet.
40. In a train control system, the combination of a track with a vehicle thereon, a mechanism having a rotating shaft driven by the movement of said vehicle, an air supply connected with said shaft and an air lock between said shaft and said mechanism comprising a plurality of grooves with a ring in each groove.
41. In a train control system, the combination of a track with a vehicle thereon, a mechanism having a rotating shaft driven by the movement of said vehicle, and an air supply connected with said shaft, an air lock between said shaft and said mechanism comprising an annular groove partially in said mechanism and partially in said shaft and a ring in said groove.
42. In a train control system, the combination of a track with a vehicle thereon, a mechanism having a rotating shaft driven by the movement of said vehicle, and an air supply connected with said shaft, an air lock between said shaft and said mechanism comprising an annular groove in said mechanism and an annular groove on said shaft, said grooves arranged to align with each other and a ring in said grooves.
43. In a train control system, the combination of a track with a vehicle thereon, and a centrifuge supported at one end and driven by the running wheels of said vehicle, said centrifuge supported at the other end by a pivot free to move in two directions at right angles to each other.
44. In a train control system, the combination of a track with a vehicle thereon, and a centrifuge supported at one end and driven by the axle of the running wheels of said vehicle and supported at the other end by a universal joint.
45. In a train control system, the combination of a track with a vehicle thereon, a centrifuge driven by the movement of said vehicle, a support for said centrifuge and an air supply for said centrifuge, and means for interrupting said air supply when said centrifuge is misplaced on its support.
46. In a train control system, the combination of a track with a vehicle thereon, a centrifuge driven by the movement of said vehicle, an air supply for said centrifuge, a support comprising a pivoted joint for said centrifuge and a yielding connection at said joint for said air supply.
47. In a train control system, the combination of a track with a vehicle thereon, a centrifuge driven by the movement of said vehicle, said centrifuge pivotally supported in a normal position and having an air supply, and means for exhausting said air supply when said centrifuge is moved from the normal position.
48. In a train control system, the combination of a track, a vehicle on said track with a pivotally supported centrifuge having an air supply and a pair of juxtaposed members with registered air ports mounted on

said pivot for conducting said air supply to said centrifuge.

49. In a train control system, the combination of a track with a vehicle thereon, a centrifuge comprising a sliding member operated by the speed of said vehicle and a controlling mechanism, said mechanism operated by said sliding member through a lever with unequal arms.

10 50. In a train control system, the combination of a track with a vehicle thereon, a centrifuge operated by the speed of said vehicle and having a sliding member, a controlling mechanism operatively connected with said sliding member and means whereby said controlling mechanism is operated to a greater extent than said sliding member.

15 51. In a train control system, the combination of a track with a vehicle thereon, a centrifuge operated by the speed of said vehicle and having a sliding member and a controlling mechanism operatively connected with said sliding member through a lost motion connection, said controlling mechanism having a bias moving it to the controlling position.

20 52. In a train control system, the combination of a track with a vehicle thereon, a controlling mechanism on said vehicle including a ratchet associated with a valve and a weighted arm for operating said ratchet.

25 53. In a train control system, the combination of a track with a vehicle thereon, a controlling mechanism on said vehicle including a valve operated by a ratchet, a weighted arm for operating said ratchet and a plurality of means for holding said arm in the raised position.

30 54. In a train control system, the combination of a track with a vehicle thereon, a controlling mechanism on said vehicle including a valve operated by a weighted arm, means for holding said arm against said weight and means for detecting the breakage or removal of said arm.

35 55. In a train control system, the combination of a track with a vehicle thereon, a controlling mechanism on said vehicle including a device operated by an arm, said arm operating by gravity to operate said mechanism and a plurality of members each independently preventing the operation of said arm.

40 56. In a train control system, the combination of a track with a vehicle thereon, a device on said track and a controlling mechanism on said vehicle responsive to said track device, said mechanism comprising a plurality of translating devices associated with a motion plate, the action of said devices being guided by said motion plate.

45 57. In a train control system, the combination of a track with a vehicle thereon, a device on said track and a controlling mechanism on said vehicle responsive to said

track device, said mechanism comprising a plurality of translating devices having shafts rotating in opposite directions and a walking beam associated with said shafts.

58. In a train control system, the combination of a track with a vehicle thereon, a device on said track and a controlling mechanism on said vehicle responsive to said track device, said mechanism comprising a plurality of translating devices associated with a motion plate and a walking beam.

63. In a train control system, the combination of a track with a vehicle thereon, a device on said track and a controlling mechanism on said vehicle responsive to said track device, said mechanism comprising a plurality of translating devices having pivoted armatures, a motion plate and a walking beam associated with said armatures and means whereby said armatures position said walking beam.

60. In a train control system, the combination of a track with a vehicle thereon, a controlling mechanism on said vehicle including a valve moved to the operative position by the action of gravity, means retaining said valve in the inoperative position and means for detecting breakage of said retaining means.

61. In a train control system, the combination of a track with a vehicle thereon, a controlling mechanism on said vehicle including a valve operated by a weighted arm, a cross-piece on said arm and a plurality of members engaging said cross-piece to prevent the operation of said valve.

62. In a train control system, the combination of a track with a vehicle thereon, a ramp on said track, a shoe on said vehicle displaced by said ramp, a translating device on said track and a plurality of devices on said vehicle energized by the displacement of said shoe for energizing said translating device.

63. In a train control system, the combination of a track with a vehicle thereon, a ramp on said track, a shoe on said vehicle displaced by said ramp, a plurality of devices on said vehicle selectively energized by the displacement of said shoe and a translating device on said track energized by said vehicle devices.

64. In a train control system, the combination of a track having a block system arranged for traffic in both directions, a vehicle on said track, devices on said track controlled by said block system, devices on said vehicle responsive to said track devices, a plurality of translating devices on said track affecting the operation of said block system and means on said vehicle controlled by said vehicle devices for selectively energizing said translating devices.

65. In a train control system, the combination of a track with a vehicle thereon, a con-

trolling mechanism on said vehicle, a circuit including a translating device for suspending the operation of said mechanism, said device having a positioning coil and a holding coil and a hand operated generator for energizing said positioning coil.

66. In a train control system, the combination of a track with a vehicle thereon, a controlling mechanism on said vehicle, an automatic stepping device for operating said mechanism and a manually controlled stepping device co-operating with said automatic stepping device to prevent said operation, said manually controlled device operated by a handle through a screw.

67. In a train control system, the combination of a track with a vehicle thereon, a controlling mechanism on said vehicle, a stepping device for operating said mechanism, a manually controlled device synchronized with said stepping device to prevent said operation and means whereby said manually controlled device has a slow action.

68. In a train control system, the combination of a track with a vehicle thereon, a controlling mechanism on said vehicle, a stepping device for operating said mechanism, a manually controlled device synchronized with said stepping device to prevent said operation and means whereby a predetermined time interval is required for the op-

eration of said manually controlled device.

69. In a railway traffic controlling system, the combination of a track with a vehicle thereon, a device clamped to and spaced from the rail of said track, a device on said vehicle responsive to said track device for producing a retarding effect on said vehicle and means secured to said rail for detecting the operative position of said clamped device.

70. In a railway traffic controlling system, the combination of a track with a vehicle thereon, a device clamped to the rail of said track, a device on said vehicle responsive to said track device for producing a retarding effect on said vehicle, and means secured to said rail co-operating with means secured to said clamped device for controlling a circuit whereby the operative position of said clamped device is detected.

71. In a train control system, a track with a vehicle thereon, a centrifuge driven by the movement of said vehicle on the track, a mechanism operated by said centrifuge according to the speed of the vehicle, a source of energy controlled by said centrifuge and means whereby said energy normally tends to move said mechanism to a position corresponding with its position when said vehicle is running.

MATTHEW H. LOUGHridge.
